UNITED STATES PATENT OFFICE.

JOHN BURNHAM, OF BATAVIA, ILLINOIS.

IMPROVEMENT IN WATER-TANKS FOR RAILROADS.

Specification forming part of Letters Patent No. 93,052, dated July 27, 1869.

To all whom it may concern:

Be it known that I, JOHN BURNHAM, of Batavia, in the county of Kane and State of Illinois, have invented a new and valuable Improvement in Water-Tanks for Railway-Station; and I do hereby declare that the following is a full, clear, and exact description of the construction and operation thereof, reference being had to the annexed drawings making a part of this specification, in which—

Figure 1 represents a sectional view of my water-tank, and Fig. 2 a top external view with a portion of the cover broken off to show the dead-air chamber beneath.

My invention relates to tanks and apparatus at railway stations designed for supplying water to locomotives; and it consists mainly in the novel arrangement and application of devices intended to serve as efficient means for supplying water to locomotives, and of preserving such water from freezing while it remains in such tanks.

The letter H of the drawings represents a water-cistern, usually placed in the ground. In case the tank is placed over living water, such as a stream or pond, this cistern may be dispensed with. Upon the cistern H (or, in case there be no cistern, over the living fountain) I erect a frame, of which the letters D represent the posts, and letters M cross-bars, to serve as supports for the tank, next mentioned. The letter A represents my water-tank, arranged upon its frame, at such an altitude above the railway track as to bring its bottom above the boiler of the locomotive, to enable the water to pass by its own gravity from the tank to such boiler. It is usually of a circular form, constructed of staves, marked a on the drawings, and surrounded with hoops, marked b. The letters C of the drawings represent chambers, both at the top and bottom of my tank, formed by the construction of double covers and bottoms for said tank, and intended to serve as receptacles for imprisoned air. I may, and sometimes do, construct similar chambers, extending around the sides of the tank; but for all ordinary use the chambers at top and bottom are

sufficient for the purpose contemplated. In a tolerably mild climate the chamber in the top alone will answer the required purpose. In the lower chamber C I arrange supports, represented by letter s; and in both the upper covers I construct man-holes, and close them with removable trap-doors, as shown at v. Care must be taken in all cases to keep the chamber C air-tight, except when opened by the trap-door v. The letter E represents the pipe through which the water is passed, by pumping, from the cistern to the tank; and letter F an escape-pipe, that conducts the water from the tank to the cistern, when it has reached the desired height in said tank. The letter G represents the conduit through which the water is passed from the tank to the locomotive. The letters n represent ladders, arranged respectively in the tank and cistern. The space between the bottom of the tank and the top of the cistern, immediately around the pipes E and F, is inclosed in an air-tight chamber, and, if necessary, it is filled with suitable packing, to prevent said pipes from becoming inoperative by the freezing of water therein. I also, when desirable, pack the chambers C with such commodities as will aid in preventing the water in the tank from becoming frozen, as that is the sole end and object of said chambers.

I do not claim, broadly, the invention of the chambers C, for I am aware that chambers of a similar form have been used in refrigerators; nor do I claim, broadly, the invention of the pipes E and F; but

What I do claim as my invention, and desire to secure by Letters Patent, is—

The water-tank for railway stations, herein described, having chambers C, man-holes, and trap-doors v, pipes E and F, and conduit G, when constructed and arranged substantially as and for the purposes specified.

JOHN BURNHAM.
